UNITED STATES PATENT OFFICE.

THADDEUS GALVIN, OF DETROIT, MICHIGAN.

MEANS FOR FLUSHING SEWERS.

SPECIFICATION forming part of Letters Patent No. 394,166, dated December 11, 1888.

Application filed September 13, 1888. Serial No. 285,325. (No model.)

To all whom it may concern:

Be it known that I, THADDEUS GALVIN, a citizen of the United States, residing at Detroit, county of Wayne, State of Michigan, have invented a certain new and useful Improvement in Means for Flushing Sewers; and I declare the following to be a full, clear, and exact description of the invention, such as will enable others skilled in the art 10 to which it appertains to make and use the same, reference being had to the accompanying drawings, which form a part of this specification.

In the drawings, Figure 1 is a plan view 15 illustrating my invention. Fig. 2 is a longitudinal sectional view more particularly illustrating the features of construction. Fig. 3 is a cross-sectional view. Fig. 4 represents a variation in which the water-conduit is formed 20 integral with a sewer-pipe along its upper portion. Fig. 5 is a separate view of one of the nipples or leaders.

It is the purpose of my invention to provide 25 a sewer or sewer-pipe with a water-supply pipe for flushing the same, said water-supply pipe located along the top on the outside of the sewer-pipe and communicating therewith by nipples or leaders passed therefrom in through the wall of the sewer or pipe; also, in 30 providing said nipples or leaders with perforations at the front and rear adjacent to its end, and also at the sides, if desired, whereby the water is discharged in the several directions to wash down and clear away matter 35 which may collect within the pipes or sewers.

My invention consists, also, in other novel 40 features of construction, as will be more particularly specified in the claims.

In carrying out my invention, A represents 45 a sewer or sewer-pipe.

B is a water-supply pipe, which leads along the top of the sewer upon the outside of the same.

B' represents nipples or leaders extending 50 from the water-supply pipe through the wall of the sewer or sewer-pipe to the inside thereof. These leaders may be provided with a through-opening, or the end may be plugged and the leader be provided with orifices b, 55 through which the water may be discharged in sharp jets to the front and rear, and also to the sides, if desired.

The operation of this portion of the device is as follows: Sediment having gathered within the sewer or sewer-pipe, water is turned on 55 through the water-supply. This water, entering through the nipples, is discharged through the jets throughout the whole length of the water-pipe, and each jet wears away the sediment at that particular part, and 60 the flow of water quickly reduces the obstruction and operates to thoroughly flush and wash out the sewer. Each said water-pipe is provided with a valve or gate, C, for admitting or shutting off the water at 65 will. So, also, I prefer to provide each said water-pipe with a trap, D; or, instead of a trap, it may be simply a plugged pipe leading to the surface of the ground. This is for the 70 purpose of affording a ready means of discovering whether the impediment in the sewer is above or below this particular point. If it is above this point, the sewer being clear at this point, no particular odor would be discovered at this opening. If, however, the 75 impediment was below this point, the odor upon removing the plug or cap would be strong, and so the impediment might be quickly located, and when located could be cleansed by the introduction of water through the corresponding pipe, B. The leaders B' having 80 been passed through the sewer-pipe or through the wall of the sewer, the spaces about the said leaders are thoroughly stopped, so as to admit of no leakage at these points. 85

I am aware that it is not new to lead a water-supply pipe of this character upon the interior of a sewer close to its upper wall. It is manifest, however, that in constructions of this character the pipe must be introduced 90 and sustained by brackets or otherwise along the upper wall, and that to accomplish this location of the water-pipe the sewer must needs be of sufficient dimensions for a workman to pass through it upon the interior. So, 95 also, such a construction practically prohibits its use in the large mass of sewer-pipes, which are rarely of such dimensions as to admit a person through them. Moreover, this construction, whereby the water-pipe is located 100 upon the outside of the sewer, admits of its ready connection with any sewer-pipe or sewer, no matter how long the sewer might have been laid, and affords at all times ready

access to the said flushing-pipes by uncovering the sewer.

In making sewer-pipe or sewer-tiles a water-conduit might be formed integral with the 5 same along its upper portion and provided with orifices *b* at intervals leading into the sewer. Such a construction is shown in the variation in Fig. 4.

Each of the valves is preferably provided 10 with a box, *E*, leading to the surface of the ground to facilitate access thereto.

The trap *D'* is preferably provided with a valve, *d*, whereby it may be emptied when it is desired to test for sewer-stench; or the trap 15 may be dispensed with entirely, as shown in Fig. 4.

F is another flushing-valve, which may or 20 may not be employed, and if employed is for the purpose of throwing a large stream into the sewer.

What I claim is—

1. The combination, with a sewer or sewer-pipe, of a water pipe or conduit extending along its top upon the exterior of the same 25 and provided at intervals with nipples or leaders *B'*, extending through the wall of the sewer or pipe, and means for admitting and

cutting off the water therefrom at will, substantially as described.

2. The combination, with a sewer or sewer-pipe, of a water-pipe extending along the top upon the exterior of the same and provided at intervals with nipples or leaders *B'*, said leaders stopped at their extremities and provided with lateral orifices *b*, and valves or 35 gates for admitting water to or cutting it off from the pipe, substantially as described.

3. The combination, with a sewer and a flushing-pipe, *B B'*, of a gate or valve for governing the admission of water thereto, and a 40 testing pipe or trap, *D*, substantially as and for the purposes described.

4. The combination, with a sewer pipe or tile, of a water-conduit formed in its upper portion, formed integral therewith and provided with discharge-orifices *b'*, leading to the 45 interior of the sewer, substantially as and for the purposes described.

In testimony whereof I sign this specification in the presence of two witnesses.

THADDEUS GALVIN.
